UNITED STATES PATENT OFFICE

MARK H. MARTIN, OF BALTIMORE, MARYLAND, ASSIGNOR TO THE SYMINGTON COMPANY, OF NEW YORK, N. Y., A CORPORATION OF MARYLAND

DRAFT DEVICE

Application filed August 24, 1925. Serial No. 52,061.

This invention relates to draft devices and more particularly to a preferably integral casting adapted for application at the ends of car underframes, so as to cooperate with 5 the coupler, center sills and draft keys of a car.

The principal object of my invention, generally considered, is the provision of an integral draft device which is formed to function as a coupler striking and carrier iron with rearwardly extending ears preferably functioning as cheek plates for a railway vehicle or car, said member being preferably connected so as to embrace the ends of operating center sills.

An object of my invention is the provision of a combined striking casting and coupler carrier iron with rearwardly extending portions serving as Farlow or double slotted 20 cheek plates connected with the center sills on the outer surfaces thereof.

Another object of my invention is the provision of a combined casting adapted for connection at the end of a car so as to embrace 25 the adjacent ends of the center sills, the length of said casting being such that it extends beyond the ends of said sills to increase the effective length thereof and make it possible to utilize shorter sills.

30 A further object of my invention is the provision of an improved construction for car underframes and particularly the end portions thereof wherein an integral member is provided embracing the ends of the center sills thereof and holding the same more rigidly in position, said member being provided 35 with rearwardly extending portions connected with said center sills and slotted for the reception of draft keys, the edges of said slots being flanged with the flanges extending into cooperating slots in the center sills for more securely connecting said casting and center sills together, the slots in the center 40 sills extending to the adjacent ends thereof for facilitating the application of the casting thereto, said center sill ends being also coped for the reception of a web connecting portions of said casting, the top of said web, 45 when the members are assembled, being sub-

stantially flush with the tops of the center sills.

A still further object of my invention is the improvement in underframe construction wherein an integral casting is employed for connecting the ends of the center sills and acting as a combined striking casting and cheek plates, the cheek plate portions of said casting being either of the Farlow, that is the double slotted, type, or single slotted, the 55 adjacent ends of the center sills being correspondingly slotted to the ends thereof so as to embrace flanges framing the cheek plate portion slots.

Other objects and advantages of the invention, relating to the particular arrangement and combination of parts, will become apparent as the description proceeds.

Referring to the drawings illustrating my invention, the scope whereof is defined by the 70 claims:

Figure 1 is a central vertical longitudinal sectional view through a car underframe embodying the various features of my invention.

75 Figure 2 is a partial plan and partial horizontal sectional view on the line 2—2 of Figure 1.

Figure 3 is a partial end view of the construction illustrated in Figures 1 and 2.

80 Figure 4 is a partial transverse sectional view on the line 4—4 of Fig. 2, looking in the direction of the arrows.

Figure 5 is a partial transverse sectional view on the line 5—5 of Figure 2, looking 85 in the direction of the arrows.

Figure 6 is a partial view corresponding to Figure 1 but showing a modification.

Figure 7 is a partial sectional view on the line 7—7 of Figure 6.

90 Figure 8 is a partial plan and partial horizontal sectional view on the line 8—8 of Figure 9, corresponding to Figure 2 but showing another modification.

Figure 9 is a central vertical longitudinal view further illustrating the same modification.

Figure 10 is a partial end view of the construction illustrated in Figures 8 and 9.

Referring to the drawings in detail, in 100

which like parts are designated by like reference characters, there are illustrated rail-way vehicle center sills 1 also functioning as draft sills, connected to a cover plate 2 and 5 a body bolster, or the bolster transoms, 3, in a well known manner. Between the transversely extending portions of the body bolster 3 a center filler casting 4, which is also 10 preferably adapted to function as a draft rig- 10 ging back stop, is employed. The bolster top cover plate 5 preferably extends over the center sill cover plate 2 in the usual manner and the bottom bolster cover plate 6 extends below said main bolster portions or transoms 15 3, a center plate 7 being applied beneath the bottom cover plate 6 and the casting 4, in accordance with usual practice.

At the end of the center sills 1 there is connected an integral draft device 8, said device 20 being preferably formed as a casting with a coupler striking portion 9, a carrier iron portion 10, and rearwardly or inwardly extending ears or cheek plate portions 11. Said cheek plate portions, in the embodiment illus- 25 trated in Figures 1 to 5, inclusive, are shown doubly slotted or of the Farlow type, that is, each portion is provided with an outer or forward slot 12 adapted for the reception of a front draft key 13 and an inner or rear slot 30 14 for the reception of a rear draft key 15. Said cheek plate portions 11 are preferably connected to the outer sides of the webs 16 of the center sills 1, the slots 12 and 14 there- 35 in being preferably framed by flanges or beading 17 therearound. Said beading or flanged portions 17 preferably extends both ways from the web 18 of the cheek plate por- 40 tions 11, the inwardly extending portions thereof being embraced in correspondingly slotted portions 19 of the center sills, where- 45 by the strength of connection therebetween is much improved. The slots 19 in the center sills preferably extend as continuous slots clear to the adjacent ends thereof whereby 50 the combined casting 8 may be assembled with said center sills after the same have been connected together and to the other associated parts of the car underframe. That is, 55 from the corresponding end of the car with the flanged portions 17 moving in the slots 19 of the center sills to the rear or inner ends of said slots.

The web 18 of the cheek plate portions 11 is 55 preferably continued for a material distance beyond the inner or rear portions of the flange 17, as indicated at 20, so as to provide for the more rigid connection with the center sill webs and for improving the strength of said 60 cheek plate portions adjacent the ends of the slots 14 therein. The web portions 20 and adjacent flanged portions 17 may, if desired, be braced together by triangular web por- 65 tions 21.

As illustrated particularly in Figure 1, the

cheek plate portions 11 are preferably connected to the webs 16 of the center sills by rows of rivets above and below the slots 12 and 14, the forward portion of the draft member over the front slots, however, being 70 preferably increased in depth, thereby allowing for another row of rivets 22, said increased portions being preferably also connected by a horizontal shelf or web portion 23 extending between the cheek plate portions 11 for improving the strength of the casting.

The upper surface of said web 23, when connected with the center sills 1, is preferably flush with the upper surface of the upper flanges 24 thereof so that said center sills, and particularly the upper flange portions 24 thereof, are coped, notched or cut away, as indicated at 25, for the reception of said flange or shelf portion 23. The cover plate 28 35 preferably extends between the upper flanges of the center sills 1 and the web portion 23, thereby serving to further strengthen the connection therebetween, common rivets being preferably provided between the web 23, cover plate 2 and end sill 26, as illustrated particularly in Figure 1.

Beyond the end of the cover plate 2 the web or shelf portion 23 of the draft casting 8 is 95 preferably offset upwardly to form the upper flange or web portion 27 of the coupler striking portion 9. From a consideration of Figure 1 particularly, it will be seen that said coupler striking portion 9 comprises, in addition to the portion 27, the upright web portion 28 and lower flange portion 29 forming a U-shaped section which may be strengthened by longitudinally extending webs 30, the rear portions of which preferably taper or decrease in depth until they merge with the web 23 at the inner edge thereof.

The coupler carrier portion 10 is preferably U-shaped in section also with a horizontal web portion 31, depending flange portions 32 and longitudinal connecting web portions 33. A wear plate, illustrated in Figure 1, may be applied over this member in accordance with the usual practice. The ends of the portions 9 and 10 of the combined casting 8 connect directly with the forward ends of the cheek plate portions 11, said ends being preferably provided with flanges 34 framing the coupler stem opening. Said flanges 34 preferably extend both inwardly and outwardly from the web 18 of the cheek plate portions 11 and bracing webs 35 and 36 preferably extend therefrom to the adjacent flange portions 17.

The lower flanges 37 of the center sills may be cut away adjacent the outer ends, as indicated at 38. The inwardly extending portions of the flanges 17 may be decreased in depth along the horizontally extending portions between the ends of the slots 12 and 14 as it is not necessary that said flanges be as 130

strong in such positions as adjacent the ends of said slots. The draft keys 13 and 15 serve to support the inner end of the coupler stem 39 and the front follower 40, respectively, and 5 operatively connect said members with, as well as support, the front portions of a yoke 41. The yoke 41, in the present instance, is shown as of the horizontal type, the forward arms of which are slotted for the reception of 10 said draft keys 13 and 15 and the rear or U-shaped portion of which preferably abuts against the back stop member 4 and embraces the rear follower 42.

Between the front follower 40 and rear follower 42, a cushioning mechanism, illustrated diagrammatically by dot and dash lines, may be employed. For supporting the rear or inner end of the yoke 41, angular bracket members 43, preferably riveted to 20 the webs 16 of the draft sills by counter-sunk rivets 44, are employed. For supporting the cushioning mechanism, usual forms of carrier irons 45, connected to the lower flanges 37 of the center sills in any desired manner, 25 may be utilized.

In the embodiment of my invention illustrated in Figures 6 and 7, a similar construction of combined casting 8^a is utilized with the exception that the cheek plate portions 30 11^a are merely formed with a single slot 12^a in each portion so that the draft sill slot 19^a for receiving the slot flanges 17^a need not be continued from the ends of the center sill webs 16^a for as great a distance. Separate 35 cheek plates 46 may then be employed for the reception of the second or rear draft key 15^a. In this instance the web 47 of said second cheek plate is shown continued to a materially greater distance to the rear of the slot 14^a 40 therein for providing the necessary riveting area, and separate slots 48 in the center sill web 16^a for the reception of the flanges 49 may be considerably longer than necessary for said flanges so that a flanged reinforcement 45 50 in said slot 48 to the rear of the rear portion of said flanges 49, may be employed.

In the embodiment illustrated in Figures 8, 9 and 10, a casting 8^b is employed which 55 may be similar to the casting 8 or 8^a previously described with the following exceptions. In the previous modifications described it was necessary to cope or cut away the end portions of the upper flanges 24 of the center sills 1, and no direct connection was provided 60 between the combined castings 8 and 8^a and the lower flange 37 of said center sills. With the modified form of casting 8^b, however, the upper web or shelf portion 23^b is made narrower between the center sills 1 so as not to necessitate cutting away the top flanges thereof. This construction provides a slot 51 in the casting 8^b for receiving each center sill, at the same time, the slots 19^b in the webs of the center sills receive the flanges 17^b of the 65 cheek plate portions 11^b of said casting. In

this modification, there is no direct connection between the inner portion of the web or shelf 23^b and the adjacent upper edges of the cheek plate portions, said upper edges being preferably reinforced by triangular or 70 tapering web or gusset portions 52 extending rearwardly from the forward flanges 34^b of the casting 8^b.

The connection between the lower portions of the casting and the lower flanges 37 of the center sills 1 is further strengthened in the present embodiment, by outstanding flange or web portions 53 overlying the lower flanges 37 of the center sills 1 and connected thereto by rivets 54. These web portions 53 are preferably braced to the casting 8^b by triangular gussets 55. In the present modification, therefore, the upper portion of the casting 8^b is slotted to avoid weakening of the ends of the sills, whereas the connection between the lower portion thereof and said sills is strengthened by the rivets 54 extending through the web portions 53 and the lower sill flanges 37.

It will be apparent that by virtue of my 90 aforescribed construction, a combined striking casting and carrier iron with integral cheek plates, which may be either singly or doubly slotted, as desired, has been provided. Such a casting is readily connected at the 95 ends of the center sills after the same have been assembled in proper relation and greatly rigidifies and reinforces the underframe construction at such places.

Although I have disclosed certain embodiments of my invention, it will be understood that modifications may be made within the spirit and scope of the appended claims. In 100 said claims the term "car" is used in its broad sense and includes all railway vehicles.

Having thus described my invention, what I claim is:

1. An integral draft device comprising portions adapted to function, respectively, as an outer coupler stop, a coupler carrier and double slotted cheek plates, said cheek plate portions being connected by a transverse web portion normally underlying and connected to the sill cover plate of the associated underframe, the sills being coped to receive 115 said portion.

2. An integral draft device comprising portions adapted to function, respectively, as a front striking casting, a coupler carrier iron and slotted cheek plates adapted for connection to the outer sides of associated center sills and provided with flanges around the edges of the slots for engaging correspondingly slotted portions in said sills, the upper edges of the cheek plates being connected 120 by an integral web portion lying directly over the slotted portions thereof.

3. An integral draft device comprising an outer portion adapted to circumscribe a coupler stem, double slotted rear portions adapt- 130

ed for connection outside of the center sills of a car, and flanges extending entirely around the slots in said rear portions for engagement with correspondingly slotted 5 portions in said center sills.

4. An integral draft device comprising an outer portion adapted to embrace a coupler stem and rear portions formed as cheek plates and adapted for application and connection 10 outside of the center sills of a car.

5. An integral draft device comprising an outer portion adapted to embrace a coupler stem and rear portions formed as cheek plates and adapted for application and connection 15 outside of the center sills of a car, said rear portions being slotted and formed with flanges surrounding the slots and adapted for insertion in corresponding slots in the center sills.

20 6. An integral draft device comprising a portion adapted to form an outer coupler abutment, portions extending inwardly therefrom and adapted to embrace the center sills of a car therebetween, said latter portions being 25 slotted for the reception of a draft key and having flanges around the edges of said slots, portions of said flanges being adapted for engagement with the edges of correspondingly slotted portions of cooperating center 30 sills of a car.

7. In combination with the center sills of a car, an integral draft device comprising portions adapted to function respectively as a striking casting and cheek plates, said 35 cheek plate portions being connected on the outer sides of said center sills and extending beyond the ends thereof, whereby the length of said sills otherwise necessary is decreased.

8. In combination with the center sills of 40 a car, an integral draft device comprising portions adapted to function, respectively, as an outer coupler stop, a coupler carrier, and double slotted cheek plates, said cheek plate portions being provided with flanges around 45 the edges of the slots therein and engaging with correspondingly slotted portions of the center sills for increasing the strength of connection therebetween, and a transverse web connecting the upper edges of said cheek 50 plates, the ends of the sills being coped to receive said web.

9. In combination with the center sills of a car, an integral draft device comprising 55 portions adapted to function respectively as a front striking casting, a coupler carrier iron and slotted cheek plates, said cheek plate portions being so positioned and connected on the outer sides of said center sills that the draft device extends beyond the ends of said 60 center sills to increase the effective length thereof.

10. In combination with the center sills of a car, an integral draft device comprising an outer portion adapted to embrace a coupler 65 stem and rear portions formed as cheek

plates and applied and connected to said center sills on the outer surfaces thereof, said rear portions being slotted and formed with flanges along the edges of said slotted portions, said center sills being correspondingly slotted with the flanged portions contained in said slots for increasing the strength of connection therebetween. 70

11. In combination with the center sills of a car, an integral draft device formed with 75 an outer portion adapted to cooperate with a coupler and rear portions adapted to function as cheek plates and connected outside of said center sills, said cheek plate portions being slotted for the reception of a draft key and formed with flanges surrounding the slots and extending into corresponding slots in the center sills, said center sill slots being extended to the adjacent ends of said sills whereby the draft device may be assembled 80 in place with respect to the sills after said sills are connected together. 85

12. In combination with the center sills of a car, an integral draft device comprising 90 an outer portion adapted to limit the inward motion of a coupler and rear portions formed to function as cheek plates connected to said center sills on the outside thereof, said cheek plate portions being slotted and formed with flanges surrounding the slots, 95 said center sills being formed with slotted portions embracing the flanged portions of the device, said center sill slots extending to the adjacent ends of the sills whereby the device may be inserted in place after the sills 100 are assembled in proper relation, said device being formed with a horizontally extending web or shelf between intermediate portions of said cheek plate portions, so arranged, with respect to the sills that the upper surface thereof is substantially flush with the upper surface of the upper center sill flanges. 105

13. In combination with the center sills of a car, an integral draft device comprising 110 a portion adapted to form an outer coupler abutment, portions extending inwardly therefrom and lying on the outside of and extending forwardly beyond said center sills, said latter portions being slotted for the reception of a draft key and having beading 115 around the edges of said slots, said cooperating center sills being correspondingly slotted for the reception of a beading therein and said slots being open at the adjacent ends of said sills to facilitate the assembly 120 with said draft device, and a portion connecting the upper edges of said cheek plates, the upper edges of said sills at the ends being notched to receive said connecting portion. 125

14. In combination with the center sills, cover plate therefor, and end sill of a car, an integral casting comprising portions serving, respectively, as a striking casting and coupler carrier iron, and provided with rear- 130

wardly extending ears connected with the webs of said center sills and a substantially horizontal shelf portion extending rearwardly from over the carrier iron portion, the 5 adjacent ends of the center sills at their upper portions being coped for the reception of portions of said shelf extending transversely beyond said sills, and a portion of said shelf extending rearwardly between the 10 sills and connected with the cover plate and end sill.

15. In combination with car center sills formed with web portions and upper and lower flanges, a combined casting comprising 15 portions serving, respectively, as a striking casting and counter carrier iron, and provided with rearwardly extending ears connected with the webs of said center sills, the lower portions of the ears adjacent the lower 20 flanges of the center sills being formed with flange portions overlying said lower flanges and connected thereto.

In testimony whereof I affix my signature.
MARK H. MARTIN.
